UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW AND REGULATOR COUPLING.

Application filed August 23, 1922. Serial No. 583,722.

To all whom it may concern:

Be it known that ERNEST E. HEINTZ, citizen of the United States, residing at Detroit, in the county of Wayne and State of Michigan, has invented certain new and useful Improvements in Window and Regulator Couplings, of which the following is a specification.

This invention relates to window regulators. It has for its object, a window regulator which has a quickly detachable connection with the sash. This connection is of such a character that the window may be removed from the window well without removing the trimming material or any of the boards around the window well.

In the drawings,—

Fig. 1 is a side elevation of door showing the trimming material removed, and equipped with my improvement.

Fig. 2 is a sectional view on the line 2—2 of Fig. 1.

Fig. 3 is a perspective of the fixture attached to the cable.

Fig. 4 is an enlarged elevational view showing the detachable connections between the sash and cable.

Fig. 5 is a similar view showing the detachable connection just after the same has been broken.

Fig. 6 is a section taken on line 6—6 of Fig. 4.

Fig. 7 is a perspective of the latch lever used in the detachable connection.

Fig. 8 is a perspective in detail showing how the sash plate is connected to the bottom of the sash.

The various parts of the window regulator will be apparent from the drawing without giving any detailed description. The regulator here shown is described and claimed more particularly in my United States Patent No. 1,486,963. It happens to be one that employs a cable *a* which winds around an elongated drum *b*, rotated by a crank handle *c* through connections which need not here be detailed. Any form of regulator of this general type may be used. It matters not whether it is a chain driven regulator or a cable driven regulator.

It is customary in regulators of this general type to employ a flexible lift member. This is usually provided with a pin which engages in a slotted plate on the bottom of the sash. This construction works very

nicely, but in case it is necessary to detach the window from the regulator, the trimming material and often some of the boards in the body have to be removed. It is the object of the present invention to wholly eliminate this trouble. Instead of an ordinary pin secured to the draft member, I employ a fixture *d*, which is simply a stamped clip that can be soldered or otherwise fastened to the cable. In its general configuration, the clip is a dovetailed tongue, that is, when viewed in plan.

On the bottom of the window sash is secured the usual plate *e*. This plate however, has a different form of slot, than is ordinarily the case. The slot extends vertically upward from the bottom and has an enlarged opening, *f*, with beveled sides. On one side of the slot, the metal is turned up to form the stop *h*. Above the slot is pivoted the latch lever *g*. The lower end of this lever is provided with a turned over ear, *i*, which is guided on the segmentally shaped pin *j*, secured to the lug *k*, struck out of the plate *e*, a coiled spring *m* normally tends to press the latch lever against the stop *h*, causing the hook or bill end of the latch lever to close the opening of the slot *f* and prevent the escape of the fixture *d* when that is in the slot. The head of the latch lever is beveled as at *o*, and projects only part way over the entrance of the slot *f*, as plainly shown in Fig. 4.

It will be obvious that the fixture *d* is fairly rigidly held on the draft member or cable. Hence when the window is detached from the regulator, and it is desired to again couple it to the regulator, all one has to do is to insert the window in the window well and cause the window plate to be guided down against the fixture *d*. The central or narrow portion of the fixture can be caused to enter the slot *f*. This will ordinarily displace the latch lever because of the bevel *o* on its head. When the fixture has passed into the main portion of the slot, the latch lever will snap behind it and ordinarily couple the two members together.

In order to release the plate from the fixture the latch lever is provided with a projecting arm *q*, which extends through the segmental slot *r* as clearly shown in Fig. 2. Some form of a tool, like a screwdriver, bar, or the like, may be inserted down into the window well between the window sash and

the wall of the window well. This tool may be swung to open the latch *g*, and permit the window to be disengaged from the cable.

What I claim is:

- 5 1. In a window regulator, the combination of a window sash, a lifting member, and a detachable coupling between the two, including a slotted plate secured to the sash, a spring-pressed latch for guarding the 10 opening in the plate, and a fixture secured to the lifting member which may ordinarily displace the latch in entering the slot in the plate, but which requires manipulation of the latch to release it.
- 15 2. In a window regulator, the combination of a window sash, a lifting member, and a detachable coupling between the two, including a slotted plate provided with an enlarged entrance slot, a bevel-headed 20 spring-pressed latch guarding the entrance of said slot, and a fixture on the lifting member that may ordinarily displace the latch by engaging the beveled head and enter the slot, but which requires manipulation 25 of the latch to release the members.
3. In a window regulator, the combination of a window sash, a lifting member, and a detachable coupling for the two, including a slotted plate provided with a stop, 30 and having an enlarged opening leading into the slot, a bevel-headed lever guarding the opening of the slot, and having a projecting arm which may be reached by a tool from the top of the window well, a spring 35 which normally presses the latch lever against the stop, and a fixture on the lifting member that ordinarily displaces the latch by engaging against the bevel head thereof and enters the slot, but which requires 40 the latch to be displaced by a tool

inserted in the top of the window well in order to release the coupling.

4. In a window regulator the combination of a window sash, a lifting member and detachable coupling between the two comprising a device that can automatically lock when the sash is engaged with the lifting member but which requires the use of a tool when the sash is disengaged from the lifting member. 45

5. In a window regulator the combination of a window sash, a lifting member and a detachable coupling between the two including an automatic latch member which permits the engagement of the two and 50 which can be disengaged by the use of a tool to retract the latch. 55

6. In a window regulator, the combination of a window sash, means for lifting the window and holding the same in any intermediate position of travel so as to govern the opening of the window, said means including a vertically traveling lifting member, and an automatic coupling between the window sash and the lifting member which causes the sash to be automatically coupled up with the lifting member when the sash is pressed down on the lifting member. 60 65

7. In a window lifting device, a window supporting member, a means for raising and lowering the supporting member, an elastic clip secured to the window frame and having an engaging nose for elastically engaging the supporting member whereby the window may be readily connected and disconnected to and from the supporting member. 70 75

In testimony whereof I affix my signature.

ERNEST E. HEINTZ.
